UNITED STATES PATENT OFFICE.

WILLIAM SOWDON, OF NEW YORK, N. Y.

DUPLICATE-WHIST APPARATUS.

SPECIFICATION forming part of Letters Patent No. 530,665, dated December 11, 1894.

Application filed April 22, 1893. Serial No. 471,489. (No model.)

To all whom it may concern:

Be it known that I, WILLIAM SOWDON, of New York city, in the county and State of New York, have invented certain new and 5 useful Improvements in Duplicate-Whist Apparatus, of which the following is a specification.

The object of my invention is to produce a simple and cheap apparatus for playing the 10 game known as duplicate whist, and which apparatus at the same time shall take up the least space and may be carried about with the cards with which the game is intended to be played with the least possible inconvenience, and in the accompanying drawings 15 forming a part hereof, I have illustrated one embodiment of my invention, in which—

Figure 1 is a top view in isometric perspective of a box or receptacle divided into three 20 compartments, each compartment containing a device shown in detail in Fig. 4, said device being represented in Fig. 1 in the position in which it will be used to support or provide a rest for the cards or hands of cards 25 when played. Fig. 2 is a view similar to Fig. 1, showing the divided receptacle with the rests or supports shown in Fig. 1 upon which are placed the dividers adapted to maintain separate the several hands of cards when 30 played, as will be hereinafter explained. Fig. 3 is a sectional view taken through line $x-x$ of Fig. 2. Fig. 4 is an enlarged detail view 35 of one of the combined lifting means and supports for the packs or separate hands of cards; and Fig. 5 is a sectional view of a box like that shown in Figs. 1 and 2 showing the lifting means or support shown in Fig. 4 in the position in which it is with a pack of cards placed thereon when the cards are not 40 in use.

It is assumed that the game of whist is well-known, and without explaining the rules of that game in this specification, but referring immediately to the apparatus embodying my invention for use in connection with such game, in the drawings A represents a box or receptacle constructed of any suitable material divided into compartments, three compartments being represented in the drawings Figs. 1 and 2, and in each of which compartments is adapted to be placed a separate pack of cards and while the drawings illus-

trate only one box, it is to be understood that to comprise a complete duplicate whist apparatus within the spirit of my invention, four 55 of such boxes may be used, and each box divided into three compartments, so that there may be contained in the four boxes, twelve separate packs of cards, that number of packs being not unusual in the game of duplicate whist; and it is also to be understood that any further number of boxes may be used, and that each box may be divided into a greater or less number of compartments. The box may also be constructed of any convenient size and shape, but preferably of the 60 shape shown in the drawings, and preferably also of pasteboard, and these boxes are designed to be supplied with covers of any convenient character, as sliding or lifting. 70

B is a device consisting of three parts or portions a , a , c , and in the method of its construction shown in the drawings, this device consists of a piece of pasteboard bent in the manner shown in Fig. 4, so as to form the 75 three distinct portions a , b , c , and in order to preserve the bent places from fracture and to provide a hinge and support therefor, one side of this pasteboard piece is lined for a portion of its distance, as shown in Figs. 3 80 and 4, with crash, canvas, linen or other suitable material D, as will be readily understood; and one of such devices is placed in each compartment of the receptacle A, and when the game is not being played, such device is placed in position in the compartments as shown in Fig. 5, with the cards C placed 85 thereon, so that by taking hold of the portion c and lifting it up the pack of cards may be readily taken out of the boxes. When the 90 cards have been thus removed, the position of the devices, or as I will call them, "rests," is reversed, as shown in Figs. 1, 2 and 3, and they are placed over one edge of the boxes, one of such rests in each compartment, one 95 end of the portion a resting on the bottom of the box A, the hinged portion of the rest, between a and b , engaging with the upper edge of one side of the box A, the portions b and c hanging over the side of the box and the lower 100 edge of the portion c resting upon the table or other platform upon which the boxes are placed.

In playing the game of whist, as the hands

are played they must be kept separate, and in order to do so I provide dividers F, shown in Fig. 2, of such dimensions that they may be packed within the compartments of the boxes and preferably appropriately lettered, numbered or otherwise marked or designated, so as to distinguish them from each other, the dividers shown in the drawings being numbered in rotation, preferably one to twelve, only four of such dividers, however, being shown in the drawings, and each of these dividers may be further marked as shown in the drawings to indicate the hand played as hand—1, hand—2, hand—3, &c., and as each hand is played the player places divider No. 1 (or the divider which is intended to denote that one hand has been played), upon one of the rests in one of the compartments in box A, and upon this divider he places the hand played; and when another hand has been played he places another divider on the previous hand of cards, and upon this second divider he places the second hand played, and he continues this until he has consumed his dividers, arranging the dividers between the separate hands in the several compartments of box A as he desires. These rests when in the position shown in Figs. 1, 2 and 3, act as supports not only for the cards but also for the dividers, holding up the cards and dividers in inclined position with one edge at the top of the box so that they may be readily inspected and handled. Thus each of the hands played are kept separate, and when the whole number of packs of cards have been consumed or when the whole number of hands or games are played as may be desired, the boxes containing the separate hands are shifted, preferably so that the persons who are partners in one series of games will take the boxes containing the hands which their opponents had in the previous series of games and will play with the hands which their opponents had, thereby duplicating the game from which the name of the game is derived.

As before stated, any number of boxes may be employed, divided into any number of compartments, there being an according number of rests; and there may also be any number of dividers and if desired these dividers or the several sets of dividers may be variously colored, as well as or without being marked, so as to distinguish them from each other. Each of the four or more boxes are also numbered,

lettered, marked or otherwise designated so as to distinguish them from each other and the character of marking which I preferably employ is as follows: One of said boxes will be marked, "Original north—Duplicate east;" another of said boxes, "Original east—Duplicate south;" another of said boxes, "Original south—Duplicate west;" and the other of said boxes "Original west—Duplicate north;" and the persons playing the game will use the appropriate box according to their position with relation to the points of the compass, after which manner the boxes are marked as just stated.

While I have described my invention in connection with the game known as duplicate whist, it is to be understood that my invention may be employed for use in other games, and I therefore intend to include within the spirit of my invention every embodiment of it for use in any game or analogous purpose; and

What I claim as my invention, and desire to secure by Letters Patent, is—

1. The combination with a game box divided into two or more compartments adapted to hold one or more packs of cards, of a rest consisting of a flat piece having an angular extension at one end thereof, so constructed that it may be used to lift the packs from the box and adapted to support the separate packs of cards in the several compartments in an inclined position, substantially as set forth.

2. An apparatus for use in games of cards consisting of a box or receptacle divided into separate compartments, dividers to separate the different hands of cards, and rests each consisting of a flat piece having an angular extension at one end thereof so constructed that it may be used to lift the packs of cards from the box, said rests being adapted to support the separate packs and dividers in the several compartments in an inclined position, substantially as set forth.

3. In a box for use in games of cards, the rest consisting of the flat portions a, the angular extension b and the upper rim c, said rest being adapted to lift the packs of cards from the box and to support the packs of cards in an inclined position, substantially as set forth.

This specification signed and witnessed this 15th day of April, A. D. 1893.

WILLIAM SOWDON.
